EYESHIELD OR VISOR

Charles L. Peffer, New York, N. Y.

Application February 7, 1942, Serial No. 429,909

2 Claims.

(Cl. 2—12)

This invention relates to eye-shields or vizors of the type used by workmen in various industries, sportsmen, automobilists and the like, for the purpose of protecting the eyes from the glare of the sun or very strong lighting. This application is a continuation-in-part of my co-pending application, Ser. No. 308,799 filed December 12, 1939.

Heretofore, most vizors or eye-shields of this general character have been composed of a crescent-shaped section of material, often of colored transparent nature and sometimes opaque. The body of the eye-shield or vizor thus constructed is in some cases, held in position on the forehead of the wearer by means of a strap or tying string extending around the back of the head, and in other instances, the vizor was incorporated in the peak or brim of a hat, cap, or other suitable article of headwear.

In vizors of prior construction, the crescent shape of the same failed to provide adequate eye protection since the curved, or upwardly extending, lower edge of the vizor tended to cross the line of vision of the wearer, particularly at the sides thereof so that the eyes when cast to one side either looked beneath the lower curved edge of the vizor or else had their view obstructed by said edge crossing the line of vision. In other words, one of the deficiencies of present-day shields, is due to the failure to provide sufficient area in the side portions of the shields to thereby protect the wearer from the rays of light at the sides.

The primary object therefore, of the present invention, is to provide a vizor in which the line of vision is at no time interrupted and by which adequate protection for the eyes, whether looking straight ahead or cast to one side is assured. I attain this desired result primarily by the shape of the vizor which is made substantially of the same width for its entire length so that the portions of the same at the sides of the head of the wearer do not have their lower edge curving upwardly, or in any way obstructing the vision, and they serve to provide areas at the sides of the head through which the vision may be directed and which will adequately protect the eyesight. A vizor of the character described is particularly useful for workmen seated adjacent one another at a bench or table and employing strong lights. The glare of said lights often disturbs an adjacent workman. This is especially true of watchmakers, engravers, jewel setters and others, to whom adequate protection of the eyes is of extreme importance.

Another object of the invention is to provide in an eye-shield of the character described, a body portion having its concave or upper edge of peculiar contour or of such a unique shape that perfect fitment of said edge of the shield against the forehead and against the temples of the wearer is assured. In present day eye-shields, the curvature of the top edge of the shield is one which extends on the continuous arc of a single circle. I have found that the curvature of the top edge of an eye-shield on a continuous arc prevents uniform downward extension of the body of the shield; causes deflection or distortion of the shield and prevents proper protection. Accordingly, an important feature of the present invention resides in the formation of an eye-shield having the central portion of its top edge formed on a relatively small radius while the portions of said edge which fit over the temples of the wearer are curved on a larger radius. With this arrangement proper fitment of the eye-shield is obtained and the body of the same will extend uniformly downward and provide a maximum of protection for the wearer.

Another object of the invention is to provide, in an eye-shield of the character described, an arrangement by which the shield will be so disposed relatively to the eyes that the vision can be directed either through the body of the shield or below it; in which the lower edge of the body of the shield will be held away from and out of contact with the face and ventilation under the shield thereby assured.

In herein setting forth the description of my improved vizor, I do not wish to be understood as limiting the invention to a vizor *per se*, since the vizor may be incorporated effectively into the peak or brim of a hat or in any other article of headwear. Therefore, in hereinafter referring to the "vizor," I wish to be understood as meaning a vizor either incorporated or not incorporated in an article of headwear.

In the accompanying drawings, wherein an embodiment of the invention is shown, Fig. 1 is a side elevation of the vizor as it appears in use; Fig. 2 is a face view of the two main portions of the vizor; Fig. 3 is a front view of the complete vizor ready for wear; Fig. 4 is a sectional view on the line 4—4 of Fig. 3, looking in the direction of the arrows; and Fig. 5 is a plan view of the vizor indicating the curvature of the top edge of the same.

In the drawings, 1 indicates the body portion of the vizor, the same being made of any suitable material and preferably of a flexible sheet mate-

rial of a transparent, semi-transparent or even opaque nature, such as green tinted Celluloid material or the like. It will be understood that the vizor may also be made of any suitable opaque sheet material.

In the form shown, the body portion 1 is of arcuate form and has its curved upper edge 2 and curved lower edge 3 extending substantially or very nearly parallel so that the width of the vizor from one of its angular ends 4 to its opposite angular end 5 is relatively uniform. The body portion 1 thus provided may be formed with a line of holes 15 or other apertures for the purpose of ventilation. A vizor body portion of the character shown may be incorporated in the brim or peak of a hat or cap as will be well understood. When used as a vizor alone without attachment to an article of headwear, I find it desirable to provide straps or fastening elements such as shown at 6. Each of these straps consists of an elongated strip or section of suitable sheet material such as Celluloid or the like, or of the same material as that of which the body portion 1 is composed. Each strap gradually widens near its point of junction with the ends of the body portion 1 and is provided with a tapered end 7 and laterally extending tab portion 8, such end 7 and tab portion 8 being shaped to provide a notch 9 between them. In securing each of the straps 6 to the body portion 1, the elements 7 and 8 are slightly overlapped at the ends of the body portion and then binding strips 10 and 11 are stitched or otherwise secured about the edges 2, 3, 4 and 5 of the body portion 1 and also about the longitudinal edges of the straps 6. This arrangement provides the finished vizor in the form shown in Fig. 3. A buckle 12 is secured on one of the straps and the other strap is passed through it in the conventional way to secure the vizor about the head of the wearer substantially as shown in Fig. 1.

When the device is worn, it will be seen that the lower edge 3 of the vizor body portion 1 extends substantially or very nearly parallel to the upper edge 2 and that the length of the body portion 1 is sufficient to provide side areas 13 and 14 disposed well in back of the eyes and just in front of the ears of the wearer. The lower edge 3 of the vizor is disposed well below the line of vision of the eyes so that even when the eyes are cast to one side, the lower edge 3 will not cross the line of vision but the eyes will instead, be directed through the body of the vizor and be thereby well protected from the glare of light. Therefore, a greater area of vision is provided since the vision is not impaired by the lower edge of the vizor sweeping upwardly to cross the eyes as is the case with so-called "crescent-shaped" vizors. At the same time the eyesight is materially protected from side glare since the substantial width of the vizor at the sides of the wearer's head provides a broad protective area so that side light glare will not penetrate under the lower edge of the rim to reach the line of vision.

In order to cause the top edge of the vizor to fit smoothly and uniformly against the forehead and temples, and to cause the vizor to be directed downwardly without distortion, so that the lower edge of the vizor will be maintained substantially parallel to its top edge, a certain curvature of the top edge 2 is necessary. That is to say, I find it desirable to form the central portion of the top edge of the vizor, or that part located between the dotted lines A and B in Fig. 5, on a

curve having a relatively short radius. In the normal vizor, I have found a curve having a radius of approximately $5\frac{1}{2}$ inches to be satisfactory for this portion of the vizor, such portion of the top edge being that fitting around the forehead. The end portions of the top edge 2 of the vizor, or those located between the line B and the line C and between the line A and the line D are curved on a much greater radius. In fact a radius of approximately $11\frac{3}{4}$ inches for these portions of the curved top edge of the vizor will be found satisfactory. Thus, by this peculiar curvature of the top edge 2, wherein the central portion of the top edge is formed on a curve whose radius is much less than that of the end portions of the top edge, an even, smooth fit of the vizor around the forehead and temples is assured and the maintenance of the lower edge of the vizor in substantial parallelism with the top edge is the result. Accordingly, the upward, irregular flexure and distortion, found in many flexible prior art vizors, is completely eliminated. The curvature of the lower edge 3 of the vizor is also of importance in securing the results herein set forth. As indicated in Fig. 5, that portion of the lower edge which is located between the lines A and B, and designated at 20 should be a curve having a radius greater than the radius of the curve of the part of the upper edge that is located between the lines A and B. I have found an arc of approximately $6\frac{3}{4}$ inches satisfactory for this portion of the lower edge. On the other hand, the radius of the curve of those portions which lie between each of the lines A and B and the respective ends 4 and 5 of the vizor, and which edge parts are indicated at 21, should have a radius greater than that of the central lower edge portion 20, but considerably less than the radius of the upper edge between the lines A and B and the respective ends 4 and 5 of the vizor. For the curve of the lower edge in the areas 21, a radius of approximately $8\frac{5}{8}$ inches has been found satisfactory. This particular combination of curvatures for the upper and lower edges of the vizor results in a vizor capable of efficiently functioning as herein set forth.

What I have herein described the vizor as separate and distinct from an article of headwear, it will be readily understood that the same may be easily incorporated in a cap, hat or other article without departing from the spirit of the invention.

What I claim is:

1. In an eye-shield of the character described, wherein there is provided a body portion of sheet material adapted for positioning forwardly and laterally of the eyes of the wearer, said body portion having a top edge provided with a central part curved on a relatively small radius and having end portions of substantially greater radius than that of the arc of the central portion, said body portion being of a length as to have its ends terminate in proximity of the ears of the wearer, the shield when in position on the head of the wearer having the arcuate body portion thereof forwardly and downwardly directed with the lower edge of the body portion disposed below and laterally of the eyes, the lower portion of said shield being out of contact with the face, the central portion of the lower edge of the body portion having a greater radius than the central portion of the upper edge, and the end portions of the lower edge having a smaller radius than the similar end portions of the upper edge.

2. An eye-shield for protection from light rays, said shield consisting of an arcuate section of sheet material, the upper and lower edges of said shield being curved on lines nearly parallel to one another, the curvature of the upper edge of said shield being such that the central portion of said edge overlying the forehead is curved on a small radius, while those portions of said edge located adjacent to the ends of the shield are curved on a substantially larger radius, whereby the upper edge of the shield will uniformly fit around the forehead and temples and the lower edge of the shield will extend substantially parallel to said top edge, the curvature of the upper edge of the shield being such that when said edge is in contact with the forehead and temples of the wearer, the re-

mainder of the shield will extend angularly downward and over the eyes but away from and out of contact with parts of the face, said shield being of such length that the opposite ends of the shield are disposed in front of and adjacent to the ears of the wearer and the lower edge is spaced away from the face of the wearer, the central portion of the lower edge of the body portion having a greater radius than the central portion of the upper edge, and the end portions of the lower edge having a greater radius than the radius of the central part of the lower edge, said end portions of the lower edge having a smaller radius than the similar end portions of the upper edge.

CHARLES L. PEFFER.
